UNITED STATES PATENT OFFICE.

JOHN H. OSBORNE, OF PHILADELPHIA, PENNSYLVANIA, ASSIGNOR TO
LEWIS S. COX, OF SAME PLACE.

DESIGN FOR A KNIT FABRIC.

SPECIFICATION forming part of Design No. 17,195, dated March 15, 1867.

Application filed November 16, 1866. Serial No. 219,094. Term of patent 3½ years.

To all whom it may concern:

Be it known that I, JOHN H. OSBORNE, a citizen of the United States, residing in Philadelphia, Pennsylvania, have invented a new and original Design for a Knitted Fabric, of which the following is a specification.

My design is fully shown in the accompanying drawing. The groundwork F is composed of the solid knitted fabric, and on this groundwork are a number of equidistant parallel raised ribs, f, of heavier thread than that composing the groundwork. Occupying the spaces between these ribs, and extending from one parallel rib to another in right lines, are floated threads a, arranged in a zigzag form.

Irrespective of the color employed, I claim—
The design for knitted fabric, comprising a solid groundwork, parallel raised ribs f, and the floated threads a, in zigzag form, extending from one parallel rib to another in a right line, all substantially as described and shown. 20

In testimony whereof I have signed my name to this specification in the presence of two subscribing witnesses.

JOHN H. OSBORNE.
